UNITED STATES PATENT OFFICE.

JOHN J. HAWXHURST, JR., OF BROOKLYN, AND EDWARD F. NICOLAI, OF PORT WASHINGTON, NEW YORK.

KEROSENE CARBURETOR.

1,412,000.

Specification of Letters Patent.

Patented Apr. 4, 1922.

Application filed July 26, 1916. Serial No. 111,336.

To all whom it may concern:

Be it known that we, JOHN J. HAWXHURST, Jr., and EDWARD F. NICOLAI, residents, respectively, of Brooklyn, in the county of 5 Kings and State of New York, and Port Washington in the county of Queens and State of New York both citizens of the United States, have invented certain new and useful Improvements in Kerosene Carburetors, of which the following is a specification.

Our invention relates to carburetors designed for use with internal combustion engines; and more particularly to that type or 15 class of carburetors designed for use with self-propelled vehicles, and in which a preliminary mixture containing too much fuel to burn properly is first formed by the atomizing action of a current of air caused to 20 flow past a fuel supply nozzle by the suction or vacuum producing action of the engine, which rich preliminary mixture is afterward diluted to produce a proper combustible mixture by a further quantity of air admitted or permitted to flow into a suitable 25 mixing chamber wherein the preliminary mixture and the diluting air are thoroughly mixed with one another; the supply of additional air being regulated and controlled 30 by an automatically operating auxiliary air valve also dependent for its operation upon the suction action of the engine.

An object of our invention is to provide 35 a carburetor in which the outlet passage leading to the engine is permanently open and uncontrolled, as by a throttle valve, and in which the suction or vacuum producing 40 action of the engine acts at all times directly upon the elements which cooperate to form the rich preliminary mixture irrespective of whether or not additional air to dilute the mixture thus formed is being permitted to 45 flow into the mixing chamber; whereby the suction of the engine is at all times effective to secure a sufficient supply of fuel, and a 50 proper atomization thereof, irrespective of speed and load conditions under which the engine is operating and irrespective of whether or not additional air is being admitted to the mixing chamber by the auxiliary air valve.

A further object of our invention is to provide a carburetor in which the speed of the engine is regulated by the valve which

permits the admission of additional or diluting air to the mixing chamber; or in which throttling of the supply of combustible mixture to the engine is accomplished, and the speed of the engine controlled, by the auxiliary air inlet valve.

Further objects of our invention are to provide a carburetor in which a better and more economical production of the combustible mixture necessary to supply the engine when it is running without load, or idling, is secured; to provide a carburetor in which the extent of opening movement of the auxiliary air valve may be controlled manually, and independently of the means concerned with the automatic operation of said valve, so that throttling and the speed of the engine may be regulated and controlled by means of said valve; to provide a carburetor in which the adjustment necessary to secure continuous and uniform operation of the engine at low speed, as when it is running without load, may be more readily made than heretofore; to provide a carburetor which is simple in construction and effective for the purpose for which it is designed, and one in which the combustible mixture will be more nearly uniform throughout the entire range of speed and load conditions of the engine with which it is used, than has been the case in prior carburetors of the type to which our invention relates; and to otherwise improve upon and enhance the efficiency of carburetors designed for use with internal combustion engines.

With the above and other objects of invention in view, our invention consists in the improved carburetor for internal combustion engines illustrated in the accompanying drawings, described in the following specification, and particularly claimed, and in such variations and modifications thereof as will be obvious to those skilled in the art to which our invention relates.

In the drawings accompanying and forming a part of this application and wherein the preferred embodiment of our invention is illustrated, and wherein the same reference numerals are employed to designate like parts in the several figures;

Figure 1 is a view showing a section of our improved carburetor taken upon a vertical central plane indicated by the line 1—1, Figure 2;

Figure 2 is a view showing the same in plan;

Figure 3 is a view showing a section taken upon a horizontal plane indicated by the line 5 3—3, Figure 1;

Figure 4 is a view showing a section taken upon horizontal planes indicated by the broken line 4—4, Figure 1;

Figure 5 is a view showing a section taken 10 upon a vertical transverse plane indicated by the line 5—5, Figure 4; and

Figure 6 is a fragmentary view employed 15 to illustrate certain features of the fuel supply controlling valves of our carburetor, and showing a slightly modified arrangement of some of the elements thereof.

In the drawings, and referring particularly to Figure 1, the reference numeral 6 designates the exterior casing of our improved carburetor which serves as a support 20 for, or which contains the various elements which cooperate to produce a combustible mixture suitable for use by the engine with which the carburetor is used; and 7 designates a mixing chamber located within the casing and within which chamber, in the normal operation of the engine, a rich preliminary mixture of air and fuel is mixed with additional air entering through a port 25 or ports 8 and thus diluted to form a mixture containing the proper quantities of air and fuel for use in the engine; the combustible mixture flowing from the casing through an outlet passage 9 and to the engine through 30 a suitable conduit not shown, as will be understood. This casing is provided with a transverse wall or partition 10 having an opening 11, and the same is shown as made up of separate upper and lower sections secured 35 together by means of lugs 12 through which screws 13 extend, see Figure 4, to thereby provide a unitary casing; although this is a detail of construction employed for convenience in making the casing, rather than an indispensable feature of our invention, as will be appreciated from the concluding 40 claims wherein the essential features of our invention are pointed out and specified.

Located within the lower portion of the 50 casing 6 is a comparatively large air chamber 14 having a top wall 15 spaced apart from and extending approximately parallel with the transverse wall 10, and the said lower portion is provided with a double side 55 wall whereby an interior heating chamber 16 is provided which includes the space between the partition 10 and top wall 15 and surrounds the air chamber 14, and through which heating chamber a heating medium, such as exhaust gases from the engine, may be made to flow by means of suitable conduits connected with passages 17 leading into said heating chamber, the heating chamber being divided by a suitable partition 18 in

order to secure a proper circulation of the 65 heating medium about the air chamber, as will be appreciated. The air chamber is shown as open at its lower end, and said lower end as closed by a suitable cover 19, having openings 20 through which air enters 70 the chamber; and which cover serves as a support for certain of the elements concerned with the supply of fuel to the carburetor, as will hereinafter appear.

The top wall 15 of the air chamber 14 is 75 spaced apart from the transverse wall 10 as shown, from which it is obvious that the heating medium employed will flow between these walls and across the top of as well as around the air chamber; and the said top 80 wall is provided with an opening 21 located in line with the opening 11 in the wall 10. Extending across the space between these walls and having its ends lying within the openings aforesaid in said walls is a tubular 85 heating member past the exterior of which the heating medium flows, and through which the rich preliminary mixture flows on its way to the mixing chamber, whereby the said preliminary mixture is heated on its 90 way to the mixing chamber and a more perfect vaporization of the liquid fuel thus secured; said heating member being shown as comprising a series of separate tubes 22 the ends of which are secured in heads 23, 24, 95 lying within the openings 11 and 21, and the lower of which is in threaded engagement with the latter of said openings, whereby the heater as a whole may be removed for the purpose of cleaning the same; said heater 100 having also a central tube 25 through which the stem or shank of a fuel valve 26 extends. It therefore follows that the preliminary mixture in flowing through the heater is divided into a plurality of separate and independent streams, and that the heating medium flows around and between said tubes, whereby an effective heating of the preliminary mixture and thorough vaporization of the liquid fuel is secured.

The air which is mixed with the liquid fuel to form the rich preliminary mixture herein referred to flows through the openings 20 and into the comparatively large heated air chamber 14 wherein a considerable 115 reservoir of heated air always exists; and from said chamber through the tubes 22 of the preliminary mixture heater and into the mixing chamber 7; the elements enumerated constituting a vertically extending permanently open and uncontrolled primary air inlet passage leading into the mixing chamber, as will be understood. This passage is preferably contracted to provide a venturi at 27 formed in a neck 28 depending from 120 the top wall 15, and 29 designates the fuel supply nozzle of our improved carburetor through which liquid fuel is supplied to the 125

stream of air as it flows to the mixing chamber and which fuel is atomized by the action of the air as it flows past the nozzle, as will be understood.

5 The opening 11 extends through an annular portion or neck 30 extending upwardly from the partition 10 and having an annular valve seat 31 at its upper end and surrounding the upper end of the primary air 10 inlet passage above referred to; and 32 designates a vertically movable auxiliary air inlet valve, the same having a seating surface 33 adapted to cooperate with the valve seat 31 to interrupt the flow of air through 15 the ports 8 and into the mixing chamber when the valve is in its lowermost position shown in Figure 1, and to permit diluting air to flow into the mixing chamber when said valve occupies a higher position and 20 its seating surface is out of contact with the valve seat 31; the space between the valve seat 31 and the seating surface 33 when the said seating surface is out of contact with the valve seat, the adjacent space 25 within the carburetor casing, together with the ports 8 forming an auxiliary air inlet passage controlled by the air valve and leading into and through which air may flow to the mixing chamber, as will be understood. The air valve is provided with a cross bar or spider 34 to which the upper 30 end of the shank or stem of the fuel valve 26 is connected, so that the fuel valve is carried by and partakes of the movements 35 of the auxiliary air inlet valve.

The inner surface of the carburetor casing is formed with two concentric portions 35, 36, of different diameters, and the periphery of the auxiliary air valve 32 is provided 40 with two concentric portions 37, 38, of different diameters adapted to move in contact with the concentric portions of the casing, whereby an air chamber 39 is provided between the valve and casing; and 40 designates a passage in the wall of the air valve and through which the air chamber 39 is placed in communication with the interior 45 of the carburetor. Means are provided for regulating the action of the air chamber 39, the same comprising an air inlet passage 41 having a check valve 42 opening toward 50 the air chamber, the flow of air through the passage 41 being controlled by an adjustable needle valve 43.

55 The auxiliary air valve 32 is moved upward automatically and by the suction of the engine which reduces the pressure within the air chamber by withdrawing air therefrom through the passage 40, thus permitting 60 atmospheric pressure to act upon the enlarged lower portion 38 of the valve. This upward movement will take place rapidly if the flow of air through the air inlet passage 41 is restricted by the valve 43,

and slowly if the air may flow freely through 65 said passage, all as explained more fully in our application for patent for carburetor for internal combustion engines, filed upon March 3, 1916, Serial Number 81,865, which, since the filing of this application, has resulted in United States Letters Patent No. 1,210,799, dated January 2nd, 1917; and in which, among other features, an auxiliary air valve and an air chamber similar to the one herein illustrated, is claimed. 75

Means are provided in our improved carburetor for limiting the extent of upward movement of the air valve due to the suction of the engine, and for positively moving said valve downward and in opposition to 80 the suction to thereby reduce the supply of diluting air and thus throttle the supply of combustible mixture to the engine, said means being shown as comprising an oscillating shaft 44 supporting in bearings 85 provided in the carburetor casing and operated through an arm 45 from any suitable point and through suitable connections, said shaft carrying a cam 46 which engages a stop member 47 pivotally supported at 48 from the casing and so located as to engage or be engaged by the upper end of the air valve, all as shown in Figure 1 of the drawing; from which it follows that upward movement of the air valve will be arrested when 90 the stop member is swung upward and into contact with the cam, and that the cam may be rotated to force the valve downward so as to cut off to a greater or less extent the flow of air through the auxiliary air inlet 100 passage and into the mixing chamber.

In Figure 1, the various parts are shown in the positions which they occupy when the engine is to be started and, the supply of diluting air to the mixing chamber being 105 cut off because of the engagement of the seating surface 33 with the valve seat 31, the entire suction or vacuum producing action of the engine will act directly at the fuel supply nozzle and produces a strong 110 and effective atomizing action at said nozzle; whereas, if the outlet passage 9 were provided with a throttle valve to be partly closed at starting, the vacuum producing action of the engine would be for the most 115 part expended in producing a flow past the throttle valve, with the result that the velocity of air past the fuel supply nozzle would be reduced to such an extent as to seriously interfere with if not entirely defeat the atomizing action of the said air. 120

At starting, then, the mixture supplied to the engine is formed by the air which enters through the primary air inlet passage, and such air flows past the fuel supply nozzle 125 at high velocity, because of the direct action of the suction produced by the engine at the fuel supply nozzle due to the absence of a

throttle valve in the outlet from the carburetor, from which it follows that a copious and sufficient supply of fuel for starting is secured and that the fuel is thoroughly 5 atomized and vaporized.

After the engine has been started the cam 46 is rotated in order to permit the stop member 47 to rise and the engine to attain its normal speed, during which increase in 10 speed the air valve moves upward due to the partial vacuum within the carburetor casing as hereinbefore explained, and an increasing quantity of air is permitted to flow past the auxiliary air valve and into 15 the mixing chamber, as will be understood.

The adjustment of the carburetor relative to the engine is such that the air valve follows and its upper end keeps in contact with the stop member 47 as the cam 46 is moved, 20 so that the position of the cam always determines the maximum speed of the engine. If, however, it is desired to reduce the speed of the engine, the air valve is moved downward by the cam 46 acting through the stop 25 member 47, whereby the supply of diluting air to the mixing chamber is reduced and the supply of combustible mixture to the engine is throttled. This action, however, is not accompanied by such a change in the 30 mixture supplied to the engine as to impair its burning qualities as because of an insufficient fuel supply, faulty atomization, or otherwise, for the reason that in our carburetor the suction of the engine always acts 35 directly at the fuel nozzle as the throttling is accomplished by the auxiliary air valve, and the throttling operation is accompanied by an increase rather than by a reduction of the supply of fuel, and by a more vigorous 40 rather than by a diminishing atomizing action because of the greater velocity of the flow of the stream of air past the fuel supply nozzle at such times. Finally, should the speed of the engine decrease for any reason, 45 as when the vehicle encounters a hill, or should the load upon the engine be increased, the suction action within the carburetor casing will be reduced and the air valve will move downwardly, thus automatically 50 reducing the supply of diluting air and at the same time securing an increase in the velocity of flow of the stream of air past the fuel supply nozzle, which action will result in a mixture having a larger proportion 55 of fuel the combustion of which will tend to increase the power of the engine and to cause it to resume its former speed.

The auxiliary air inlet ports 8 are preferably located adjacent the upper end of the 60 primary air inlet passage, and, in order to provide for a heated supply of diluting air which may sometimes be desirable notwithstanding the heating to which the preliminary mixture is subjected, a heating 65 jacket is provided which extends from the

said air inlet ports downward to the lower end of the carburetor casing; which jacket is spaced apart from the casing and is open at its lower end whereby an annular air passage 49 is provided, and whereby the diluting air will be heated by the outer wall of the heating chamber 16 as it flows through the passage above referred to. The jacket here contemplated is preferably made of two similar parts or sections, 50, 50, so 70 shaped as to fit about the carburetor casing, as shown, and said parts are held together and upon the casing by means of screws 51 extending through lugs formed upon the sections, whereby a heating jacket is provided which may be readily attached to or removed from the carburetor.

The cover 19 for the heated air chamber 14 is provided with a fuel supply passage 52, and with a downwardly extending inferiorly treaded tubular extension or supporting member 53, the interior of which communicates with said fuel supply passage, as shown; and the reference numeral 54 designates a tubular member in threaded 85 engagement with the interior of said extension and extending up into the air chamber and terminating adjacent the venturi opening 27.

The fuel supply nozzle 29 is located within 90 and movable longitudinally of the tubular member 54, to which end said nozzle is provided with a depending portion operatively connected with a rotary nozzle adjusting member 55 in threaded engagement with the 100 interior of the extension 53; said nozzle adjusting member having an operating arm 56, and suitable packing being provided therefor, as shown.

The purpose of the mechanism for vertically adjusting the fuel supply nozzle above explained is to enable the carburetor to be so adapted to the engine with which it is used as to produce a mixture containing such quantities of air and fuel that the engine 110 may be readily started when the auxiliary air inlet valve is in its lowermost position, as hereinbefore explained, and to produce a mixture suitable for use when the engine is running without load, or idling; as well 115 as to also provide an adjustment whereby a proper supply of fuel may be secured when the engine is operating under normal speed and load conditions, and when diluting air is being admitted to the mixing 120 chamber; it being obvious that downward movement of the fuel supply nozzle will be accompanied by an increase in the quantity of fuel supplied whatever may be the position of the air valve and fuel valve carried 125 thereby, and vice versa.

The liquid fuel supply passage 52 communicates with a fuel passage 57 formed in the bottom wall of a fuel reservoir 58, the interior of which is divided by a partition 130

- 59 into two compartments; which compartments communicate with the passage 57 through ports 60, 61, the flow through which is controlled by vertically moving reciprocating fuel valves 62, 63, having upwardly extending stems 64, 65, which extend through the top wall or cover 66 of the fuel reservoir and are provided with grooved collars 67, 68.
- 10 Supported from the top wall or cover of the reservoir 58 is an oscillating fuel supply valve operating member having an arm 69 through which it may be operated from a distance and forked valve operating arms 15 70, 71, which engage the collars 67, 68, aforesaid; from which it will be obvious that when said lever and valves are in the positions shown in Figure 1, fuel will flow from the right hand compartment of the 20 fuel reservoir, while if the operating arm 69 be moved to the right the valve 63 will be moved so as to close the port 61, and the valve 62 so as to open the port 60, whereupon fuel will be supplied from the left 25 hand compartment of the fuel reservoir.
- In order to hold the valve operating member and the fuel valves operated thereby in either of the extreme positions assumed by said parts the valve stems 64, 65, 30 are provided with inclined surfaces 72 adjacent their upper ends, and 73 designates spring pressed holding members located in housings 74, upon the cover of the fuel reservoir, one of which members, depending 35 upon which of the valves 62, 63, is in its lowermost position, is pressed against the inclined surface 72 of the valve stem of the valve in question, thus forcing the said valve downward into firm contact with its 40 seat and holding it in that position until the valve operating member is operated to seat the other valve, as will be understood from Figure 6 of the drawings. In this Figure 6 the housings 74 are shown as arranged 45 at right angles to the positions which they occupy in the other figures, see particularly Figure 2, in order to better illustrate the construction and operation of the valve operating mechanism as a whole in a single 50 figure; the figure in question thus showing a modified arrangement of the housings upon the cover 66 of the full reservoir.
- The two compartments of the fuel supply reservoir are supplied from any suitable 55 sources with two kinds of fuel, such as gasoline and kerosene, the former being used at starting and the latter after the engine has been started, as hereinbefore explained; said fuels being supplied through inlet conduits 75, 76, and the flow through said conduits being controlled by floats 77, 78, within the chambers, as shown and as is usual in carburetors of the type to which our invention relates.
- 60 Having thus described and explained our 65 invention, we claim and desire to secure by Letters Patent:—
1. In a carburetor of the class described, a suitable casing having a mixing chamber, a permanently open and uncontrolled primary air inlet passage leading into said mixing chamber, and of sufficient capacity to furnish the air necessary for forming a combustible mixture for the engine with which the carburetor is used when the engine is idling an auxiliary air inlet passage leading into said mixing chamber, and a permanently open and uncontrolled outlet passage leading from said mixing chamber; a nozzle through which fuel is supplied to said primary air inlet passage; a suction operated auxiliary air valve adapted to control the flow of air through said auxiliary air inlet passage; and means for regulating the extent of movement of said auxiliary air valve. 75
2. In a carburetor of the class described, a suitable casing having a mixing chamber, a permanently open and uncontrolled primary air inlet passage leading into said mixing chamber, an auxiliary air inlet passage leading into said mixing chamber, and a permanently open and uncontrolled outlet passage leading from said mixing chamber; a nozzle through which fuel is supplied to said primary air inlet passage; a suction operated auxiliary air valve adapted to control the flow of air through said auxiliary air inlet passage; and means for regulating the extent of movement of said auxiliary air valve. 80
3. In a carburetor of the class described, a suitable casing having a mixing chamber, a permanently open and uncontrolled primary air inlet passage leading into said mixing chamber, an auxiliary air inlet passage leading into said mixing chamber, and a permanently open and uncontrolled outlet passage leading from said mixing chamber; a nozzle located within said primary air inlet passage; a suction operated auxiliary air valve adapted to regulate the supply of air to said mixing chamber; and a fuel valve connected with and operated by said auxiliary air valve and adapted to control the flow of fuel through said fuel supply nozzle. 85
4. In a carburetor of the class described, a suitable casing having a mixing chamber, a vertically extending permanently open and uncontrolled primary air inlet passage leading into said mixing chamber, a series of auxiliary air inlet ports through which air may flow into said mixing chamber, and a permanently open and uncontrolled outlet passage leading from said mixing chamber; a vertically movable annular air valve lo- 90

- 130

cated within said casing and adapted to regulate the supply of air to said mixing chamber; a fuel supply nozzle located within said primary air inlet passage; and a fuel valve 5 carried by said auxiliary air valve and adapted to control the flow of fuel through said fuel supply nozzle.

5. In a carburetor of the class described, a suitable casing having a mixing chamber, a 10 vertically extending permanently open and uncontrolled primary air inlet passage leading into said mixing chamber, a series of auxiliary air inlet ports through which air may flow into said mixing chamber, and a 15 permanently open and uncontrolled outlet passage leading from said mixing chamber; a vertically movable suction operated annular air valve located within said casing and adapted to regulate the supply of air to said 20 mixing chamber; means for regulating the extent of upward movement of said auxiliary air valve; a fuel supply nozzle located within said primary air inlet passage; and a fuel valve carried by said auxiliary air 25 valve and adapted to control the flow of fuel through said fuel supply nozzle.

6. In a carburetor of the class described, a suitable casing having a mixing chamber, a vertically extending permanently open and 30 uncontrolled primary air inlet passage leading into said mixing chamber, a series of auxiliary air inlet ports through which air may flow into said mixing chamber, and a permanently open and uncontrolled outlet 35 passage leading from said mixing chamber; a vertically movable suction operated annular air valve located within said casing and adapted to regulate the supply of air to said mixing chamber; an adjustable stop 40 member adapted to limit the extent of upward movement of said auxiliary air valve; a fuel supply nozzle located within said primary air inlet passage; and a fuel valve carried by said auxiliary air valve and adapted 45 to control the flow of fuel through said fuel supply nozzle.

7. In a carburetor of the class described, a suitable casing having a mixing chamber, a vertically extending permanently open and 50 uncontrolled primary air inlet passage leading into said mixing chamber, a series of auxiliary air inlet ports through which air may flow into said mixing chamber, and a permanently open and uncontrolled outlet 55 passage leading from said mixing chamber; a vertically movable annular air valve located within said casing and adapted to regulate the supply of air to said mixing chamber, the inner surface of said casing having 60 concentric portions of different diameters, and the periphery of said air valve having also concentric portions of different diameters adapted to move in contact with the concentric portions of said casing, where- 65 by an air chamber is provided between said

valve and casing; a fuel supply nozzle located within said primary air inlet passage; and a fuel valve carried by said auxiliary air valve and adapted to control the flow of fuel through said fuel supply nozzle.

8. In a carburetor of the class described, a suitable casing having a mixing chamber, a vertically extending permanently open and uncontrolled primary air inlet passage leading into said mixing chamber, a series of auxiliary air inlet ports through which air may flow into said mixing chamber, and a permanently open and uncontrolled outlet passage leading from said mixing chamber; a vertically movable annular air valve located within said casing and adapted to regulate the supply of air to said mixing chamber, the inner surface of said casing having concentric portions of different diameters, and the periphery of said air valve having also concentric portions of different diameters adapted to move in contact with the concentric portions of said casing, whereby an air chamber is provided between said valve and casing; manually operable means 85 adapted to regulate the extent of upward movement of said auxiliary air valve; a fuel supply nozzle located within said primary air inlet passage; and a fuel valve carried by said auxiliary air valve and adapted to 90 control the flow of fuel through said fuel supply nozzle.

9. In a carburetor of the class described, a suitable casing having a mixing chamber, a vertically extending permanently open and uncontrolled primary air inlet passage leading into said mixing chamber, a series of auxiliary air inlet ports through which air may flow into said mixing chamber, and a permanently open and uncontrolled outlet 100 passage leading from said mixing chamber; a vertically movable annular air valve located within said casing and adapted to regulate the supply of air to said mixing chamber, the inner surface of said casing 105 having concentric portions of different diameters, and the periphery of said air valve having also concentric portions of different diameters adapted to move in contact with the concentric portions of said casing, whereby an air chamber is provided between said valve and casing; means for regulating the action of said air chamber; means for regulating the extent of upward movement of said auxiliary air valve; a fuel supply nozzle 110 located within said primary air inlet passage; and a fuel valve carried by said auxiliary air valve and adapted to control the flow of fuel through said fuel supply nozzle.

10. In a carburetor of the class described, a suitable casing having a mixing chamber, a vertically extending permanently open and uncontrolled primary air inlet passage leading into said mixing chamber, a series of auxiliary air inlet ports through which air 115

- may flow into said mixing chamber, and a permanently open and uncontrolled outlet passage leading from said mixing chamber; and a vertically movable suction operated annular air valve located within said casing and adapted to regulate the supply of air to said mixing chamber; the capacity of said primary air inlet passage being sufficient to furnish the air necessary for forming a combustible mixture for the engine with which the carburetor is used when the engine is running at low speed.
11. In a carburetor of the class described, a suitable casing having a mixing chamber, a vertically extending permanently open and uncontrolled primary air inlet passage leading into said mixing chamber, a series of auxiliary air inlet ports through which air may flow into said mixing chamber, and a permanently open and uncontrolled outlet passage leading from said mixing chamber; a vertically movable annular air valve located within said casing and adapted to regulate the supply of air to said mixing chamber, the inner surface of said casing having concentric portions of different diameters, and the periphery of said air valve having also concentric portions of different diameters adapted to move in contact with the concentric portions of said casing, whereby an air chamber is provided between said valve and casing; and means for regulating the extent of upward movement of said auxiliary air valve.
12. In a carburetor of the class described, a suitable casing having a mixing chamber, a vertically extending permanently open and uncontrolled primary air inlet passage leading into said mixing chamber, a series of auxiliary air inlet ports through which air may flow into said mixing chamber, and a permanently open and uncontrolled outlet passage leading from said mixing chamber; a vertically movable annular air valve located within said casing and adapted to regulate the supply of air to said mixing chamber, the inner surface of said casing having concentric portions of different diameters, and the periphery of said air valve having also concentric portions of different diameters adapted to move in contact with the concentric portions of said casing, whereby an air chamber is provided between said valve and casing; and means for regulating the extent of upward movement of said auxiliary air valve.
13. In a carburetor of the class described, a suitable casing having a mixing chamber, a vertically extending permanently open and uncontrolled primary air inlet passage leading into said mixing chamber, a series of auxiliary air inlet ports located adjacent the upper end of said primary air inlet passage and through which air may flow into said mixing chamber, and a permanently open and uncontrolled outlet passage leading from said mixing chamber; an annular valve seat surrounding the upper end of said primary air inlet passage; a vertically movable annular air valve located within said casing and having an annular seating surface adapted to co-operate with said valve seat; a fuel supply nozzle located within said primary air inlet passage; and a fuel valve carried by said auxiliary air valve and adapted to control the flow of fuel through said fuel supply nozzle.
14. In a carburetor of the class described, a suitable casing having a mixing chamber, a vertically extending permanently open and uncontrolled air inlet passage leading into said mixing chamber, a series of auxiliary air inlet ports located adjacent the upper end of said primary air inlet passage and through which air may flow into said mixing chamber, and a permanently open and uncontrolled outlet passage leading from said mixing chamber; an annular valve seat surrounding the upper end of said primary air inlet passage; a vertically movable suction operated annular air valve located within said casing and having an annular seating surface adapted to co-operate with said valve seat; means for regulating the extent of upward movement of said auxiliary air valve; a fuel supply nozzle located within said primary air inlet passage; and a fuel supply valve carried by said auxiliary air valve and adapted to control the flow of fuel through said fuel supply nozzle.
15. In a carburetor of the class described, a suitable casing having a mixing chamber, a vertically extending air inlet passage leading into said mixing chamber, a series of auxiliary air inlet ports located adjacent the upper end of said primary air inlet passage and through which air may flow into said mixing chamber, and a permanently open and uncontrolled outlet passage leading from said mixing chamber; an annular valve seat surrounding the upper end of said primary air inlet passage; a vertically movable suction operated annular air valve located within said casing and having an annular seating surface adapted to co-operate with said valve seat; an adjustable stop member adapted to regulate the extent of upward movement of said auxiliary air valve; a fuel supply nozzle located within said primary air inlet passage; and a fuel valve carried by said auxiliary air valve and adapted to control the flow of fuel through said fuel supply nozzle.
16. In a carburetor of the class described, a suitable casing having a mixing chamber, a vertically extending permanently open and uncontrolled primary air inlet passage leading into said mixing chamber, a series of auxiliary air inlet ports located adjacent the upper end of said primary air inlet passage and through which air may flow into

the upper end of said primary air inlet passage and through which air may flow into said mixing chamber, and a permanently open and uncontrolled outlet passage leading from said mixing chamber; an annular valve seat surrounding the upper end of said primary air inlet passage; a vertically movable annular air valve located within said casing and having an annular seating surface adapted to co-operate with said valve seat, the inner surface of said casing having concentric portions of different diameters, and the periphery of said air valve having also concentric portions of different diameters adapted to move in contact with the concentric portions of said casing, whereby an air chamber is provided between said valve and casing; a fuel supply nozzle located within said primary air inlet passage; and a fuel valve carried by said auxiliary air valve and adapted to control the flow of fuel through said fuel supply nozzle.

17. In a carburetor of the class described, a suitable casing having a mixing chamber, a vertically extending permanently open and uncontrolled primary air inlet passage leading into said mixing chamber, a series of auxiliary air inlet ports located adjacent the upper end of said primary air inlet passage and through which air may flow into said mixing chamber, and a permanently open and uncontrolled outlet passage leading from said mixing chamber; an annular valve seat surrounding the upper end of said primary air inlet passage; a vertically movable annular air valve located within said casing and having an annular seating surface adapted to co-operate with said valve seat, the inner surface of said casing having concentric portions of different diameters, and the periphery of said air valve having also concentric portions of different diameters adapted to move in contact with the concentric portions of said casing, whereby an air chamber is provided between said valve and casing; means for regulating the extent of upward movement of said auxiliary air valve; a fuel supply nozzle located within said primary air inlet passage; and a fuel supply valve carried by said auxiliary air valve and adapted to control the flow of fuel through said fuel supply nozzle.

18. In a carburetor of the class described, a suitable casing having a mixing chamber, a vertically extending permanently open and uncontrolled primary air inlet passage leading into said mixing chamber, a series of auxiliary air inlet ports located adjacent the upper end of said primary air inlet passage and through which air may flow into said mixing chamber, and a permanently open and uncontrolled outlet passage leading from said mixing chamber; an annular valve seat surrounding the upper end of said primary air inlet passage; a vertically movable

air valve located within said casing and having an annular seating surface adapted to co-operate with said valve seat, the inner surface of said casing having concentric portions of different diameters, and the periphery of said air valve having also concentric portions of different diameters adapted to move in contact with the concentric portion of said casing, whereby an air chamber is provided between said valve and casing; means for regulating the action of said air chamber; means for regulating the extent of upward movement of said auxiliary air valve; a fuel supply nozzle located within said air inlet passage; and a fuel valve carried by said auxiliary air valve and adapted to control the flow of fuel through said fuel supply nozzle.

19. In a carburetor of the class described, a suitable casing having a mixing chamber, a vertically extending air inlet passage leading into said mixing chamber, a series of auxiliary air inlet ports located adjacent the upper end of said primary air inlet passage and through which air may flow into said mixing chamber, and a permanently open and uncontrolled outlet passage leading from said mixing chamber; an annular valve seat surrounding the upper end of said primary air inlet passage; and a vertically movable suction operated annular air valve located within said casing and having an annular seating surface adapted to co-operate with said valve seat.

20. In a carburetor of the class described, a suitable casing having a mixing chamber, a vertically extending permanently open and uncontrolled primary air inlet passage leading into said mixing chamber, a series of auxiliary air inlet ports located adjacent the upper end of said primary air inlet passage and through which air may flow into said mixing chamber, and a permanently open and uncontrolled outlet passage leading from said mixing chamber; an annular valve seat surrounding the upper end of said primary air inlet passage; a vertically movable annular air valve located within said casing and having an annular seating surface adapted to co-operate with said valve seat, the inner surface of said casing having concentric portions of different diameters, and the periphery of said air valve having also concentric portions of different diameters adapted to move in contact with the concentric portions of said casing, whereby an air chamber is provided between said valve and casing; and means for regulating the extent of upward movement of said auxiliary air valve.

21. In a carburetor of the class described, a suitable casing having a mixing chamber, a vertically extending permanently open and uncontrolled primary air inlet passage leading into said mixing chamber, a series of

- auxiliary air inlet ports located adjacent the upper end of said primary air inlet passage and through which air may flow into said mixing chamber, and a permanently open 5 and uncontrolled outlet passage leading from said mixing chamber; an annular valve seat surrounding the upper end of said primary air inlet passage; a vertically movable air valve located within said casing and 10 having an annular seating surface adapted to co-operate with said valve seat, the inner surface of said casing having concentric portions of different diameters, and the periphery of said air valve having also concentric portions of different diameters 15 adapted to move in contact with the concentric portion of said casing, whereby an air chamber is provided between said valve and casing; means for regulating the action 20 of said air chamber; and means for regulating the extent of upward movement of said auxiliary air valve.
22. In a carburetor of the class described, a suitable casing having an air chamber 25 open at one side, and a heating chamber for heating said air chamber; a mixing chamber; a primary air inlet passage leading from said air chamber and discharging into said mixing chamber; an auxiliary air inlet 30 passage leading into said mixing chamber; a cover for closing the open side of and having an opening leading into said air chamber; and a fuel supply nozzle carried by said cover and through which fuel is 35 supplied to said primary air inlet passage.
23. In a carburetor of the class described; a suitable casing having an air chamber open at one side, and a heating chamber for heating said air chamber; a mixing chamber; a primary air inlet passage leading from said air chamber and discharging into said mixing chamber; an auxiliary air inlet passage leading into said 40 mixing chamber; a cover for closing the open side of and having an opening leading into said air chamber; a fuel supply nozzle carried by said cover and through which fuel is supplied to said primary air inlet passage, a tubular heating member included 45 in said primary air inlet passage; and means for heating said heating member.
24. In a carburetor of the class described, a suitable casing having a transverse partition; an air chamber having a top wall 50 spaced apart from said partition; a heating chamber for heating said air chamber and which heating chamber includes the space between said partition and top wall; an air inlet passage leading from said air chamber 55 and extending across the space between said top wall and partition and discharging into said mixing chamber; a fuel supply nozzle through which fuel is supplied to said air inlet passage; and an outlet passage leading 60 from said mixing chamber.
25. In a carburetor of the class described, a suitable casing having a transverse partition; an air chamber having a top wall spaced apart from said partition; a heating chamber for heating said air chamber and which heating chamber includes the space between said partition and top wall; and a primary air inlet passage leading from said air chamber and extending across the space between said top wall and partition and discharging into said mixing chamber; an auxiliary air inlet passage leading into 70 said mixing chamber; a fuel supply nozzle through which fuel is supplied to said air inlet passage; and an outlet passage leading from said mixing chamber.
26. In a carburetor of the class described, a suitable casing having a transverse partition; an air chamber open at its bottom and having a top wall spaced apart from said partition; a heating chamber for heating said air chamber and which heating chamber includes the space between said partition and top wall; an air inlet passage 75 leading from said air chamber and extending across the space between said top wall and partition and discharging into said mixing chamber; a cover for closing the open bottom of and having an opening leading into said air chamber; a fuel supply nozzle through which fuel is supplied to said air inlet passage; and an outlet passage leading 80 from said mixing chamber.
27. In a carburetor of the class described, a suitable casing having a transverse partition provided with an opening; an air chamber having a top wall spaced apart from said partition and having also an opening; a heating chamber for heating said air chamber and which heating chamber includes the space between said partition and top wall; a mixing chamber; an air inlet 90 passage leading from said air chamber and discharging into said mixing chamber; a tubular heating member included in said air inlet passage and extending across the space between said top wall and partition and the ends of which lie within the openings aforesaid in said elements; a fuel supply nozzle through which fuel is supplied to said air inlet passage; and an outlet passage leading 95 from said mixing chamber.
28. In a carburetor of the class described, a suitable casing having a transverse partition provided with an opening; an air chamber having a top wall spaced apart from said partition and having also an opening; a heating chamber for heating said air chamber and which heating chamber includes the space between said partition and top wall; a mixing chamber; a primary air inlet passage leading from said air chamber and discharging into said mixing chamber; an auxiliary air inlet passage leading into 105 said mixing chamber; a fuel supply nozzle through which fuel is supplied to said air inlet passage; and an outlet passage leading 110 from said mixing chamber.
29. In a carburetor of the class described, a suitable casing having a transverse partition provided with an opening; an air chamber having a top wall spaced apart from said partition and having also an opening; a heating chamber for heating said air chamber and which heating chamber includes the space between said partition and top wall; a mixing chamber; a primary air inlet passage leading from said air chamber and discharging into said mixing chamber; an auxiliary air inlet passage leading into 115 said mixing chamber; a fuel supply nozzle through which fuel is supplied to said air inlet passage; and an outlet passage leading from said mixing chamber.

- member included in said primary air inlet passage and extending across the space between said top wall and partition and the ends of which lie within the openings aforesaid in said elements; a fuel supply nozzle through which fuel is supplied to said primary air inlet passage; and an outlet passage leading from said mixing chamber.
29. In a carburetor of the class described, 10 a suitable casing having a transverse partition provided with an opening; an air chamber open at its bottom and having a top wall spaced apart from said partition and having also an opening; a heating chamber for 15 heating said air chamber and which heating chamber includes the space between said partition and top wall; a mixing chamber; a primary air inlet passage leading from said air chamber and discharging into said mixing chamber; an auxiliary air inlet passage 20 leading into said mixing chamber; a tubular heating member included in said primary air inlet passage and extending across the space between said top wall and partition, 25 and the ends of which lie within the openings aforesaid in said elements; a cover for closing the open bottom of and having an opening leading into said air chamber; a fuel supply nozzle carried by said cover and 30 through which fuel is supplied to said primary air inlet passage; and an outlet passage leading from said mixing chamber.
30. In a carburetor of the class described, 35 a suitable casing having a mixing chamber, an air chamber located below said mixing chamber and open at its bottom, a vertically extending primary air inlet passage extend-
- ing from said air chamber to said mixing chamber, an auxiliary air inlet passage leading into said mixing chamber, and an outlet 40 passage leading from said mixing chamber; an air valve adapted to control the flow through said auxiliary air inlet passage; a cover for closing the lower end of and having an opening leading into said air chamber; a vertically adjustable fuel nozzle carried by said cover; and a fuel valve connected with and operated by said air valve and adapted to control the flow of fuel 45 through said fuel supply nozzle.
31. In a carburetor of the class described, 50 a suitable casing having a mixing chamber, an air chamber open at one side, an air inlet passage extending from said air chamber to said mixing chamber, and an outlet passage 55 leading from said mixing chamber; a cover for closing the open side of and having an opening leading into said air chamber; an interiorly threaded supporting member carried by said cover; a tubular member carried 60 by said supporting member and extending into said air chamber; a fuel supply nozzle located within said tubular member; a rotary adjusting member operatively connected with said nozzle and in threaded engagement with the interior of said supporting member; and a fuel supply conduit in communication with the interior of said supporting member.
- In testimony whereof, we have signed our 70 names to this specification this 19th day of July, 1916.

JOHN J. HAWXHURST, JR.
EDWARD F. NICOLAI.
